UNITED STATES PATENT OFFICE.

WALLACE L. BAKER, OF PAINESVILLE, OHIO.

METAL CORNER FOR OIL-CLOTHS, &c.

SPECIFICATION forming part of Letters Patent No. 250,637, dated December 13, 1881.

Application filed October 7, 1881. (No model.)

To all whom it may concern:

Be it known that I, WALLACE L. BAKER, of Painesville, in the county of Lake and State of Ohio, have invented certain new and useful 5 Improvements in Metal Corners for Oil-Cloths, &c.; and I do hereby declare the following to be a full, clear, and exact description of the invention, such as will enable others skilled in the art to which it pertains to make and use 10 it, reference being had to the accompanying drawings, which form part of this specification.

My invention relates to metallic binding; and it consists, as an article of manufacture, of a sheet-metal corner-piece struck up from 15 a single piece of sheet metal, and consisting of a plate provided with a vertical flange and also a second flange struck up from the body of the plate.

In the drawings, Figure 1 is a plan view of 20 a metal corner constructed according to my invention. Fig. 2 is a vertical sectional view of Fig. 1 through the line *x x*. Fig. 3 is an isometric view of the bottom or lower side of a metal corner constructed according to my 25 invention.

In the said drawings, A represents the body 30 of the corner-piece, which is adapted to cover the corner of oil or other cloth, provided with a flange, B, which flange is at right angles with the main body of the corner-piece, and when in position is adapted to rest upon the floor outside of the oil or other cloth whose corner it protects. A second flange, C, is struck 35 up from the body A upon its inner corner, which forms a heavy bearing upon the oil or other

cloth which the corner encompasses, and is intended to hold the corner rigidly in place.

I am aware that heretofore it has been common to bind the edges of oil and other floor cloths with narrow strips of metal, known as 40 "edging," such sheet-metal strips being bent around the four sides of the cloth, covering the edges thereof to protect them and prevent the edges from wearing.

I am also aware that corner-pieces have been 45 made provided with a flange which has V-shaped portions cut from it, so that it may be adapted to inclose the edge of the oil or other cloth and be bent down upon its under side. The manufacture of such a corner is attended 50 with considerable expense, while my device can be made cheaply and quickly by simply cutting the blanks from pieces of sheet metal and striking them into form at a single operation.

What I claim is—

As a new article of manufacture, a corner-piece for oil and other cloths struck up from a single piece of sheet metal, and consisting of the body A, having the vertical flange B and 60 an interior curved flange, C, adapted to constitute a heavy bearing, substantially as set forth.

In testimony whereof I have signed my name to this specification in the presence of two 65 subscribing witnesses.

WALLACE L. BAKER.
